(57) **CLAIM**

The ornamental design for a measuring scoop, as shown and described.

DESCRIPTION

FIG. 1 is a top perspective view of a measuring scoop showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is the top plan view thereof; and,

FIG. 8 is the bottom plan view thereof.

The broken lines in the drawings depict portions of the measuring scoop that form no part of the claimed design.

1 Claim, 2 Drawing Sheets
